UNITED STATES PATENT OFFICE.

DAVID A. EBINGER, OF COLUMBUS, OHIO.

DESIGN FOR A URINAL.

51,537.

Specification for Design.

Patented Dec. 4, 1917.

Application filed September 30, 1916. Serial No. 123,183. Term of patent 14 years.

To all whom it may concern:

Be it known that I, DAVID A. EBINGER, a citizen of the United States, residing at Columbus, in the county of Franklin and State of Ohio, have invented a new, original, and ornamental Design for Urinals, of which the following is a specification, reference being had to the accompanying sheet of drawings, forming part thereof.

Figure 1 is a view in perspective showing my new design, and,

Fig. 2 is a top plan view of the structure shown in Fig. 1.

I claim:

The ornamental design for a urinal, as shown.

DAVID A. EBINGER.

Witnesses:

WALTER E. L. BOCK,
A. L. PHELPS.
